THERMOHYDROMETER

Leo Edelmann, Chicago, Ill., assignor to E. Edelmann & Co., Chicago, Ill., a corporation of Illinois

Application July 30, 1932, Serial No. 626,998

4 Claims. (Cl. 265—46)

This invention relates to improvements in thermo-hydrometers, and particularly to instruments of this character intended and adapted to be used in testing anti-freeze solutions in radiators and in other like connections.

An object of my invention is to provide an instrument of this character that can be used in testing solutions lighter than water and solutions heavier than water, without the necessity of using different scale markings, likely to cause confusion, upon the float element.

Another object is to so construct the parts that correction tables can be provided for a plurality of different solutions of different characteristics, which correction tables take into account variations due to temperature, and the user can readily determine which table is to be used and can make readings accordingly without possibility of confusion or error.

Still another object is to provide separate floats and separate correction scales for solutions lighter than water and for solutions heavier than water, together with means to insure use of the proper float and to direct attention to the proper correction table.

Still another object is to provide an instrument of this character which is relatively simple in its construction and assembly and which includes a minimum number of parts adapted to perform the functions and purposes intended.

With the above and other objects in view which will be apparent to those skilled in the art, my invention includes certain novel features of construction and combinations of parts which will be hereinafter set forth in connection with the drawings and then pointed out in the claims.

In the drawings:

Figure 1 is a view in side elevation illustrating an adaptation of my invention.

Fig. 2 is a similar view taken from the opposite side of the instrument.

Fig. 3 is a vertical sectional view through the instrument.

Fig. 4 is a transverse sectional view substantially on line 4—4 of Fig. 1.

Fig. 5 is a fragmentary vertical sectional view taken at right angles to the showing in Fig. 3.

The nozzle tip 1 has a widened head 2 thereon which is provided with socket openings 3 and 4 to receive and hold the ends of float or liquid barrels 5 and 6, which are of glass or other suitable material and can be of standard form and construction. A third socket opening 7 is provided in the head portion 2 to receive the lower end of a thermometer housing 8, and this socket

opening 7 has a passage 9 directly communicating with the passage 10 through the nozzle tip.

The head portion 2 is preferably made of rubber or other suitable and like material, and is provided with a valve recess 11 having passages 12 and 13 leading therefrom to communicate at their outer ends with the interior of the liquid and float barrels 5 and 6. A rotary plug valve 14 is inserted into the recess 11 with its stem 15 extending at one side and provided with a handle 16 in the form of a pointer, and this rotary plug valve 14 is constructed as a two-way valve to communicate selectively with the ports or passages 12 and 13. A port 17 leads from passage 9 to the valve chamber 11.

The valve structure is so constructed that as the pointer handle 16 is shifted to a position to point to float barrel 5, which may be considered as the float barrel for taking readings of solutions lighter than water, communication is established through port 12 and passage 11 from the nozzle tip 10 directly to this float barrel 5, and the port or passage 13 to float barrel 6 is closed, the reverse being true in the opposite setting of the indicating handle 16. Stops 18 and 19 are provided on the head portion 2 to limit movement of the pointer handle 16 and thus insure proper settings in each of the adjusted positions.

The thermometer housing 8 extends up substantially parallel with the parallel float housings 5 and 6, and the upper portion 20 is preferably made of glass, or other suitable transparent material. A thermometer is mounted in this thermometer housing with its bulb portion with 30 in the socket opening 7 to thus be influenced by liquid in passage 9, and the capillary tube 21 of the thermometer is carried in the transparent portion 20 and has a scale carrying member 22 mounted adjacent thereto so that readings can be 35 taken as the height of the indicating column varies in the capillary tube, due to variations in the temperature of the liquid in passage 9.

A spreader member 23 is provided to hold said float barrels 5 and 6 and the thermometer hous- 40 ing 20 in proper relation at their upper ends.

A cap 24 is provided on its lower side with socket openings 25 and 26 to receive and hold the upper ends of liquid and float barrels 5 and 6 in liquid and air-tight connections, and a socket 50 opening 27 is provided on the upper side to receive a connector sleeve 28, suction and compression bulb 29 being attached on the outer end of this connector sleeve 28. Ports 30 and 31 are provided to establish communication from the 55

suction bulb 29 to each of the float and liquid barrels 5 and 6.

Floats 32 and 33 are placed in the float and liquid barrels 5 and 6, and these floats have the stems thereof marked off with suitable scale indications. For convenience, sleeves 34 and 35 are mounted revolubly on the float barrels 5 and 6 to normally drop by gravity to the position as indicated where they will not interfere in any way with the clear view of the stems of the floats, and these sleeves 34 and 35 can have the outer surfaces thereof printed or otherwise marked to show correction tables for different liquids. For convenience in use and identification, it may be found desirable to designate and mark the float 32 as the "red" float and the float 33 as the "green" float, and when this is done correction tables or other associated markings on the sleeves 34 and 35 can be correspondingly colored or indicated so that the user will be certain that the proper float and the proper correction table or other matter are being used.

In the use of this instrument the indicating valve handle 16 can be set to open the passage to either of the barrels 5 or 6, and close the passage to the other barrel, thus rendering operative only one side of the instrument, but in either setting the liquid is drawn into passage 9 so that the thermometer bulb is submerged and thus the temperature indicating portions are influenced in either use of the instrument.

As stated, this instrument is particularly adapted for use in testing solutions heavier than water and solutions lighter than water, and in the case of anti-freeze solutions, the barrel 5 and associated parts will be used for solutions lighter than water, such as denatured alcohol solutions, and the many other solutions as put out by manufacturers under distinctive and designating trade names. Consequently, the correction scales or other matter on the sleeve 34 can be definitely and carefully reckoned and figured to give accurate data from which corrections can be made, corresponding with variations in the temperature of the liquid as indicated by the thermometer. On the other hand, the barrel 6 and associated parts will be used in testing solutions heavier than water, as for instance, glycerine, ethylene-glycol, and the several other solutions put out by manufacturers under distinctive and individual trademarks or trade names.

In making a test as for example of a radiator solution, the operator will first find out what kind of solution is contained in the radiator, then locate this solution on one of the correction tables of the instrument, the position or color of the correction table will tell whether to read the red float or the green float and will indicate the proper setting of the handle 16. Having determined the solution to be tested and the color of the float to be used in making the reading, the handle 16 is pointed to that particular float in the instrument, the operator then squeezes the bulb 29 to draw some of the solution into the barrel and it has been found desirable to draw in and expel liquid several times before making a reading in order to equalize the temperature of the instrument with the solution to be tested. The operator then manipulates the bulb 29 to draw just enough solution to raise the float from the bottom of the jar or barrel and the instrument is then ready for the reading. Following this manipulation it is assured that the liquid in the barrel is of substantially the same temperature as the liquid influencing the thermometer or other temperature re-

sponsive element and consequently the two readings can be taken as substantially accurate tests of liquid under the same conditions.

To read the instrument, the user notes the letter on the stem of the hydrometer float just above the top of the liquid, and then glances at the thermometer to note the figure on the thermometer scale nearest the top of the indicating column. With the float letter and the thermometer temperature reading in mind the operator can then readily refer to the correction table for the particular liquid solution and by reading vertically and horizontally thereon can take the figure and the meeting point of the two readings as being a final figure or result desired. As in the case of radiator solutions, it is desirable to ascertain the actual freezing temperature of the solutions being tested, and with corrections for definite readings on the float scale arranged vertically and corrections for definite readings of the thermometer scale arranged horizontally, the figure where the vertical and horizontal lines cross or meet is the actual freezing temperature of the solution being tested.

As illustrated in Fig. 1 other correction tables or data might be enclosed in the upper end of the thermometer housing 20, as indicated at 36, and a loop 37 can be provided to suspend the instrument when not in use.

While I have herein shown and described only certain specific embodiments of my invention and have set forth only certain possible modifications, it will be appreciated that other changes in the form, construction, arrangement and assembly of the parts and in the materials used in the construction, can be made without departing from the spirit and scope of my invention.

I claim:

1. A thermo-hydrometer for use in testing liquids of relatively different specific gravity comprising, a plurality of liquid barrels to provide one barrel for each of the liquids to be tested, a single liquid suction nozzle connected with each of the barrels, a single suction and expulsion means connected with each of said liquid barrels, a gauge float in each barrel calibrated for the particular liquid to be tested therein, and a single valve means associated with the nozzle to selectively open communication to any one of the liquid barrels.

2. A syringe thermo-hydrometer for use in testing a plurality of liquids of relatively different specific gravity comprising, a nozzle member provided with a main liquid passage and branched liquid passages, liquid and float barrels connected with said nozzle member in communication with each of the branched passages, a cap connected with the remaining ends of the several liquid barrels, a single suction and expulsion means connected with said cap and having communication with each of the several liquid barrels, a gauge float in each of the liquid barrels, temperature indicating means having a portion thereof within the main passage of the nozzle member to be influenced by and indicate the temperature of liquid taken into said nozzle for test in any one of the liquid barrels, and valve means to control the flow of liquid from said main liquid passage through the branched passages and consequently to the liquid barrels.

3. A syringe thermo-hydrometer for use in testing a plurality of liquids having relatively different specific gravities comprising, a nozzle member having a main liquid passage thereto and provided with a widened head having

branched liquid passages therein communicating with the main liquid passage, a plurality of liquid and float barrels connected with the nozzle head and each in communication with one of the branched liquid passages, a cap fitted to close the opposite ends of each of the liquid and float barrels and provided with a passage communicating to each of the barrels, a single suction and compression means connected with the passage connection to thus be in communication with each of the liquid barrels, a gauge float in each of the liquid barrels, a valve mounted in the nozzle head to control the flow of liquid from the main passage through the branched passages, and operating means associated with said valve means to visibly indicate the particular barrel having its branched passage connected with the main liquid passage.

4. A syringe thermo-hydrometer for use in testing a plurality of liquids having relatively different specific gravities comprising, a nozzle member having a main liquid passage thereto and provided with a widened head having

branched liquid passages therein communicating with the main liquid passage, a plurality of liquid and float barrels connected with the nozzle head and each in communication with one of the branched liquid passages, a cap fitted to close the opposite ends of each of the liquid and float barrels and provided with a passage communicating to each of the barrels, a single suction and compression means connected with the passage connection to thus be in communication with each of the liquid barrels, a gauge float in each of the liquid barrels, a valve mounted in the nozzle head to control the flow of liquid from the main passage through the branched passages, operating means associated with said valve means to visibly indicate the particular barrel having its branched passage connected with the main liquid passage, and a single temperature indicating means having a temperature influenced portion thereof located in the main passage of the nozzle portion to be influenced by liquid taken into said passage for flow to any one of the liquid barrels.

LEO EDELMANN.
